UNITED STATES PATENT OFFICE.

JAMES F. McDONNELL, OF LAKWOOD, OHIO, ASSIGNOR, BY DIRECT AND MESNE ASSIGNMENTS, TO THE McDONNELL BOTTLE CAP COMPANY.

BOTTLE-CAP.

1,233,896.

Specification of Letters Patent. Patented July 17, 1917.

Application filed October 4, 1916. Serial No. 123,617.

To all whom it may concern:

Be it known that I, JAMES F. McDONNELL, a citizen of the United States, residing at Lakewood, in the county of Cuyahoga and State of Ohio, have invented a certain new and useful Improvement in Bottle-Caps, of which the following is a full, clear, and exact description.

This invention relates to a bottle cap, and has for its object to provide a cap which when applied to and crimped onto the neck of a bottle, not only effectively seals the bottle so that leakage of the contents from, and admission of air to the bottle is prevented, but the contents of the bottle is prevented from coming in contact with any part of the cap which might be decomposed so as to affect the taste or quality of the contents.

It has been customary heretofore, to seal bottles, such as beer bottles, with a metal cap which is crimped about the neck of the bottle and which is provided with a gasket, usually in the form of a composition termed "cork", which is designed to provide an impervious seal. This gasket is generally in the form of a disk extending entirely across the interior of the cap, or in the form of an annulus or washer-like member designed to be forced down onto the top of the bottle neck.

While these devices have been more or less successful, particularly when applied with an effective capping machine, nevertheless they have not proven to be entirely satisfactory because the top edges of the bottles are frequently irregular, due to fractures or to the fact that the bottles are improperly formed originally, with the result that out of a given number of bottles which are filled and capped, the percentage of so-called "leakers" is quite large. Additionally, the contents of the bottle comes in contact with either the metal or with the gasket, causing deterioration and seriously affecting the taste of the contents of the bottle.

The invention herein described, effectively overcomes both objections.

In the drawing wherein I have shown the details of the cap, and two slightly different ways that the cap may be applied to the bottle, Figure 1 is a bottom view of the cap embodying my invention; Fig. 2 is a sectional view of the same; Fig. 3 is a perspective view of the gasket removed from the cap, part of the gasket being in section; Figs. 4 and 5 are sectional views through the cap and neck of a bottle after the cap has been applied to the latter, Fig. 4 showing the middle part of the cap indented or depressed, while Fig. 5 shows the top of the cap substantially flat or straight.

The cap, as usual, consists of a body 10 provided with a top portion 10^a and a crimped flange or skirt 10^b. Seated in the cap and located at the junction of the top 10^a and flange 10^b is a gasket 11 which is in the form of a washer or annulus, but instead of being rectangular in cross-section, as is generally the case, it is triangular in cross-section, the lower face of the gasket being inclined in the manner clearly shown in Figs. 2 and 3 for a purpose to be subsequently explained.

On the inner side of the cap I provide a thin layer 11^a, preferably aluminum, which will not be attacked or affected by the contents of the bottle. This layer may be in the form of a disk cut from a thin sheet or foil of aluminum. When this layer 11^a is employed, the iron or so-called tin of which the cap is made, is not exposed at any point within the confines of the gasket.

The effect of this construction when applied to the bottle will be apparent from Figs. 4 and 5. When the cap is applied to the neck of a bottle 12 with any of the usual capping machines, either by simply crimping or forcing the flange of the cap around the outside of the neck leaving the top flat or substantially flat as shown in Fig. 5, or by both pressing the cap about the outside of the neck and also indenting the central part of the cap as indicated at 13 in Fig. 4, the triangular shaped gasket instead of being pressed down onto the very top of the bottle as heretofore, is caused to engage around the outside of the neck of the bottle, and at the same time the metal is brought down onto the top of the neck so that the contents of the bottle comes in contact only with the aluminum coated part of the cap, and not in contact even with the gasket. The advantage of having the gasket engage the outer portion of the neck as illustrated in Figs. 4 and 5 is that a more effective seal is provided, and the percentage of "leakers" is reduced to a minimum for the reason that the irregularities or fractures

are almost invariably at the top edge of the bottle neck, and by causing the gasket to come well around the outside of the neck, the gasket is caused to engage the smooth 5 part of the neck. In capping the bottle sufficient pressure is created on the gasket to cause an impervious seal, but the disposition of the gasket is such that the great pressure which is applied by the capping 10 machine onto the neck of the bottle is taken up by the bottle itself instead of by the gasket, with the result that the gasket is not compressed into a hard solid mass as is the case when the gasket is entirely between 15 the bottle and the plunger of the capping machine. An additional advantage lies in the fact that not only does the gasket effectively seal the bottle, but it does not come in contact with the contents of the bottle, 20 the latter coming in contact only with the aluminum lined surface which will not be attacked by the contents so that the taste of the latter will not be affected.

Having thus described my invention, what 25 I claim is:

1. A bottle cap consisting of a dish-shaped piece of metal having a top and a down-turned flange, and a gasket seated on the interior of the cap at the junction of the 30 top and flange and provided with a lower tapered surface which inclines from the flange upwardly and inwardly to the top portion of the cap, said gasket being in the form of a ring or annulus having an inner

tapered surface and being thicker in the 35 middle than at its edges.

2. A bottle cap consisting of a piece of metal having a circular top and a down-turned flange, and a gasket in the form of a ring or annulus fitting into the corner at 40 the junction of the top and flange, said gasket being normally substantially triangular in cross-section so as to present an inclined surface to the top of the bottle.

3. A bottle cap consisting of a dish-shaped 45 piece of metal having a top and a down-turned flange, and a gasket seated on the interior of the cap at the junction of the top and flange and being normally substantially triangular in cross-section so as to 50 present an inclined surface to the neck of the bottle, the maximum thickness of the gasket being at the junction of the top and flange of the cap.

4. A bottle cap consisting of a piece of 55 metal having a substantially flat circular top and a down-turned flange, and a gasket in the form of a ring or annulus fitting into the corner at the junction of the top and flange, and having a lower tapered surface 60 which extends from the inner surface of the flange to the inner surface of the top, the inner surface of the cap within the confines of the gasket being covered with a disk of aluminum.

In testimony whereof, I hereunto affix my 65 signature.

JAMES F. McDONNELL.
